UNITED STATES PATENT OFFICE.

ROBERT S. WHITE, JR., OF OSCEOLA, AND CHARLES A. FRY, OF GRAND, OKLAHOMA.

FEEDER AND CUTTER FOR THRESHING-MACHINES.

No. 874,813.

Specification of Letters Patent.

Patented Dec. 24, 1907.

Application filed April 24, 1907. Serial No. 370,058.

To all whom it may concern:

Be it known that we, ROBERT S. WHITE, Jr., and CHARLES A. FRY, citizens of the United States, residing at Osceola and Grand, respectively, in the counties of Custer and Day, respectively, and State of Oklahoma, have invented new and useful Improvements in Feeders and Cutters for Threshing-Machines, of which the following is 10 a specification.

This invention relates to feeders and band cutters for threshing machines; and it has for its objects to simplify and improve the construction and operation of this class of 15 devices.

Further and special objects of the invention are to provide simple and improved means for driving the band cutting mechanism and for regulating the feed whereby the 20 speed of the feed mechanism will be relaxed or stopped entirely in case of necessity, when the throat of the machine becomes choked.

With these and other ends in view which will readily appear as the nature of the 25 invention is better understood, the same consists in the improved construction and novel arrangement and combination of parts which will be hereinafter fully described and particularly pointed out in the claims.

30 In the accompanying drawings has been illustrated a simple and preferred form of the invention; it being, however, understood that no limitation is necessarily made to the precise structural details therein exhibited, 35 but that changes, alterations and modifications within the scope of the invention may be resorted to when desired.

In the drawings, Figure 1 is a side elevation showing the improved feeding and band 40 cutting mechanism applied to the front end of the threshing machine. Fig. 2 is a side view illustrating the opposite side. Fig. 3 is a longitudinal vertical sectional view. Fig. 4 is a vertical transverse sectional view taken 45 on the plane indicated by the line 4—4 in Fig. 3. Fig. 5 is a sectional detail view of the governor. Fig. 5^a is a sectional elevation of the governor. Fig. 6 is a sectional view taken through one end of the band cutter shaft and showing the emergency governor. Fig. 7 is a sectional view taken on 50 the plane indicated by the line 7—7 in Fig. 6. Fig. 8 is a detail view showing the lower end of the lever actuating the emergency governor. Fig. 9 is a sectional detail view

showing the upper end of the lever actuating the emergency governor and the means whereby said lever is held in engagement with the actuating cam. Fig. 10 is a detail view in elevation of the actuating cam. 60

Corresponding parts in the several figures are denoted by like characters of reference.

1 designates the forward end of the casing of an ordinary threshing machine wherein is journaled the shaft 2 carrying the threshing 65 cylinder 3. The mouth of the casing 1 is expanded to form a chamber 4 in which parts of the band cutting and feeding mechanism are located.

The shaft 5 which carries the band cutting 70 knives 6 is supported in advance of and above the cylinder shaft 2, and said band cutter shaft carries a band wheel 7 which is driven direct from a pulley 8 upon the cylinder shaft by a belt 9; constant motion at 75 high speed will thus be imparted to the band cutter shaft when the machine is in motion.

The band cutter shaft carries adjacent to the band wheel 7 a wheel or disk 10 having a friction rim or flange 11 and provided with a 80 hub 12 upon which three sprocket wheels 13, 14 and 15 are formed or secured. The friction wheel 10 is loose upon the band cutter shaft and it is adapted to be driven by means of friction shoes 16 pivoted upon the spokes 85 of the band wheel 7 and normally held out of engagement with the friction rim 11 by means of springs 17 coiled upon rods 18 which are loosely connected with the friction shoes by means of apertured lugs or ears 19 90 extending from the latter; said rods being extended through apertured lugs 20 upon the band wheel, and the springs 17 being disposed between the lugs 20 and nuts 21 which are threaded upon the outer ends of the rods 95 18, so that the tension of the springs may be regulated by loosening or tightening said nuts. When the machine is at rest, the shoes 16 will hug the hub of the band wheel 7; when the machine is in motion, and attains a predetermined speed the centrifugal force acting upon the shoes 16 will force the latter against the tension of the springs 17 into engagement with the friction rim 11 of the wheel 10 which will thus be driven; it being understood that as soon as the speed falls below threshing speed the motion of the wheel 10 will be suspended. 100 105

22 is a shaft supported for rotation below and parallel to the band cutter shaft, and 110

carrying at one end the emergency governor G which includes a sleeve 23 secured by a key 23^a, as shown in Fig. 6, or other suitable means upon the end of the shaft and having 5 a pair of sprocket wheels 24 and 25 mounted loosely thereon for rotation, said sprocket wheels being of different diameters, the one designated 25 being the larger; collars 26 having set screws 27 are employed to retain 10 the said sprocket wheels against longitudinal movement upon the sleeve. The sleeve 23 has a slot 28 adjacent to which are formed bearing lugs 29 supporting a pin or shaft 30 carrying a lever 31, the outer end of which 15 is adapted to engage shoulders 32 and 33 formed upon the inner faces of the sprocket wheels 24 and 25, respectively, said sprocket wheels being, however, sufficiently spaced so that the outer end of the lever 31 may occupy 20 an intermediate position out of engagement with either of the sprocket wheels, as will be seen in Fig. 6 of the drawings. Fitted in the outer end of the sleeve 23 is a slidable shaft section 34 having at its inner end a slot 35 in 25 which the inner end of the lever 31 is accommodated; it will be readily seen that by sliding the shaft section 34 longitudinally of the band cutter shaft 22, the lever 31 may be rocked so as to place its outer end in engagement with the shoulder 32 or 33 upon the 30 sprocket wheel 24 or 25, or said lever may be adjusted at an intermediate position; the slidable shaft section 34 is automatically operated by means which will be presently 35 more fully described.

36 is a transverse shaft supported for rotation above and parallel to the band cutter shaft 5 and having a crank or cranks supporting the upper ends of the curved serrated 40 feeder bars 37 which extend downwardly and rearwardly below the band cutter shaft, intermediate and alternating with the band cutting knives, said feeder bars being vibrated when the crank shaft 36 is in motion 45 so as to push or feed the grain in the direction of the cylinder; the lower rear ends of the feeder bars 37 are provided with boxes 38 accommodating a transverse shaft 39 which is connected by means of links 40 with cranks 50 41 extending from a rock shaft 42; in this manner, the rear ends of the feeder bars will be supported without interference with their vibratory movement. The shaft 42 carries at one end a segment 43 having a cam edge 55 44, the working face of which is adapted to be engaged by a roller or anti-friction member 45 upon one end of a lever 46 which is fulcrumed exteriorly upon the casing 1 at 47, which latter represents a lug disposed intermediate 60 the shafts 42 and 22; the opposite end of the lever is bifurcated as shown at 48, and engages an annularly grooved collar 49 upon the shaft section 34 which is slidably mounted in the sleeve 23 as hereinbefore described. The end of the lever 46 which car-

ries the roller 45 extends through a slot 50 in a housing 51 which is secured exteriorly upon the casing and which contains a spring 52, held in position by a screw cap 53, and pressing against the lever 46 in such a manner as 70 to hold the anti-friction roller 45 in engagement with the cam edge 44 of the segment 43. Thus, by the oscillation of the rock shaft 42, the lever 46 will be actuated to effect adjustment of the slidable shaft section 75 34 whereby the lever 31 is rocked to place its outer extremity in engagement with one of the sprocket wheels 24 and 25, or in any convenient non-engaging position, as the case may be. The relative arrangement of the 80 parts is such that when the free ends of the feeder bars 37 are at the lowermost limit of their movements, the rock shaft 42, the segment 43 and intermediate connecting parts will be in such a position that the lever 31 85 will be in engagement with the smaller sprocket wheel 24, which will thus drive the shaft 22 at relatively high speed; the sprocket wheel 25 rotating idly upon the sleeve 23. When the free ends of the feeder bars are 90 raised to a certain extent, the shaft 42 will be rocked, and the shaft section 34 will be moved by the intermediate connections until the engaging end of the lever 31 engages the sprocket wheel 25 whereby the shaft 22 will 95 be driven at reduced speed, the sprocket wheel 24 rotating idly upon the sleeve 23. When the free ends of the feeder bars 37 are raised to their extreme limit, the result will be that the lever 31 will be rocked to a non- 100 engaging position intermediate the sprocket wheels 24 and 25, both of which will then rotate idly upon the sleeve 23, and the shaft 22 will remain stationary.

The shaft 36 carrying the vibratory feeder 105 bars is provided with a sprocket wheel 44' which is connected by a chain 45' with the sprocket wheel 14 upon the hub of the friction wheel 10 of the governor whereby said shaft will be driven.

110 Adjacent to the shaft 22, in rear and in front of and parallel to the latter are two shafts 46' and 47' carrying spur wheels 48' and 49' that mesh with a pinion 50' upon the shaft 22; the shafts 46' and 47', which are 115 thus driven, carry the beaters or agitators 51' whereby the material which is fed to the machine is shaken, agitated and loosened, so as to be fed in the best possible condition. The grain pan 52', which is disposed below 120 the shafts 22, 46' and 47', inclines downwardly towards the threshing cylinder, the rear end of said grain pan being supported upon the lip 53' of the concave 54; the forward end of the grain pan is provided with 125 boxes 55 journaled upon cranks 56 of a rock shaft 57 which has an additional crank arm 58 that is connected by a link 59 with a crank 60 upon the shaft 36, so that the operation of said shaft will impart a vibratory and recip- 130

- rotatory movement to the grain pan which is effected in discharging the loose grain into the concave of the machine.
- The feeder includes an endless carrier 61 extending through the feed trough 62 and supported at its upper end upon a shaft 63 having a sprocket wheel 64 which is driven by a chain 65 from a sprocket wheel 66 upon the shaft 46.
- 10 The operation and advantages of this invention will be readily understood from the foregoing description taken in connection with the drawings hereto annexed by those skilled in the art to which it appertains.
- 15 The bundles of grain which are to be fed to the machine are deposited upon the endless carrier 61 which, when the machine is in motion, at threshing speed, is driven from the cylinder through the medium of the 20 governor upon the band cutter shaft and the emergency governor upon the shaft 22, it being assumed that the free ends of the feeder bars 37 are, at the time of starting the machine, at the lower limit of their movements, so that the smaller sprocket wheel 24 of the emergency governor will be driven. If the machine is fed too heavily, the free ends of the feeder bars 37 will be raised thus 25 rocking the shaft 42 and operating the emergency governor to reduce the speed of the feeder; if the machine should become choked owing to overfeed, through the presence of wet grain, or any other reason, the free ends of the feeder bars 37 will be raised to their 30 utmost limit, and the endless carrier 61 will cease to operate. This, however, will not interfere with the operation of the feeder bars 37 and the band cutter shaft 5 which continue to operate until the throat of the 35 machine becomes partially cleared, when the free ends of the feeder bars will descend and motion at the proper speed will again be transmitted to the endless carrier 61 so that grain will again be fed to the machine.
- 40 45 This improved band cutting and feeding mechanism, as will be seen, is simple in construction and automatic in operation requiring no attention beyond the placing of the bundles upon the endless carrier, where- 50 by they are conveyed to the throat of the machine.
- Having thus fully described the invention, what we claim as new is:—
1. In a feeder and band cutter for threshing machines, a shaft supported for rotation, band cutting knives upon said shaft, a countershaft having cranks, serrated feeder bars pivoted upon the cranks, a rock shaft having crank arms, links connecting said arms with the free ends of the feeder bars, a segment upon the rock shaft having a cam edge, a rock lever having an anti-friction member engaging the cam edge of the segment, a countershaft driven from the band 55 cutter shaft, an emergency governor including sprocket wheels of different diameters mounted loosely thereon and driven from the band cutter shaft and means actuated by the rocking lever whereby said sprocket wheels may be operatively connected with the countershaft. 65
  2. In a band cutter and feeder for threshing machines, a cutter carrying shaft having a governor including a plurality of sprocket wheels, a countershaft, an emergency governor on said countershaft including two sprocket wheels of different diameters loose upon said shaft and driven direct from the governor upon the cutter carrying shaft, a lever operatively connected with the countershaft, shoulders upon the inner faces of the sprocket wheels adapted to be engaged by said lever, vibratory feeder bars having vertically movable free ends, and connecting means between the feeder bars and the lever connected with the countershaft whereby said lever will be rocked to engagement with either of the sprocket wheels or to an intermediate non-engaging position as the free ends of the feeder bars rise or fall to 80 different positions. 85
  3. In a band cutter and feeder for threshing machines including a countershaft having cranks, serrated feeder bars pivoted upon the cranks, a rock shaft having crank arms, and links connecting said arms with the free ends of the feeder bars, an emergency governor including a countershaft, a sleeve upon said shaft, sprocket wheels of different diameters journaled loosely upon the sleeve, bearing lugs extending from the sleeve adjacent to a slot in the latter, a lever pivoted upon said lugs, shoulders upon the inner faces of the sprocket wheels adapted to be engaged by the outer end of the lever, 95 a shaft section mounted slidably in the sleeve and having a slot engaging the inner end of the lever, and means actuated by the rock shaft having crank arms, link-connected with the feeder bars whereby the shaft section is moved longitudinally in the sleeve. 100
  4. In a band cutter and feeder for threshing machines, an emergency governor including a countershaft, a sleeve upon said shaft, sprocket wheels of different diameters 115 mounted loosely upon the sleeve and having shoulders upon their inner faces, a lever carried by and extending through a slot in the sleeve, the outer end of said lever being adapted for engagement with the shoulders upon the sprocket wheels, a shaft section slidably in the sleeve and having a slot engaging the inner end of the lever, a crank shaft supporting a plurality of feed bars, a rock shaft having cranks, links connecting the latter with the free ends of the feeder bars, a segment upon the rock shaft having a cam edge, a lever having a bifurcated end 120 125

engaging an annular groove upon the sliding shaft section of the emergency governor, an anti-friction member upon the opposite end of said lever engaging the cam edge of the 5 segment, and a spring engaging said lever to hold the anti-friction member in engagement with the cam edge of the segment.

In testimony whereof, we affix our signatures in presence of two witnesses.

ROBERT S. WHITE, JR.
CHARLES A. FRY.
